FIG. 4

UNITED STATES PATENT OFFICE

CHARLES H. WOODCOCK, OF WORCESTER, MASSACHUSETTS.

DOOR-OPENER.

SPECIFICATION forming part of Letters Patent No. 435,109, dated August 26, 1890.

Application filed April 24, 1890. Serial No. 349,295. (No model.)

To all whom it may concern:

Be it known that I, CHARLES H. WOODCOCK, a citizen of the United States, residing at Worcester, in the county of Worcester and State of Massachusetts, have invented a new and useful Door-Opener, of which the following, together with the accompanying drawings, is a specification sufficiently full, clear, and exact to enable persons skilled in the art to which this invention appertains to make and use the same.

The object of my present invention is to afford a simple, cheap, and efficient mechanism for latching and opening doors, said mechanism being adapted to be fitted into the jamb-frames to engage the edge of the door, as hereinafter explained; also, to provide a latching device furnished with push-button studs that are revealed through the face-casing at the front, or at both front and rear, for receiving pressure to actuate or retract the latch-dog, and a spring-actuated presser that exerts an opening impulse on the door when it is released by the retraction of the latch-dog. These objects I attain by mechanism such as shown and described, the particular subject claimed being hereinafter definitely specified.

In the drawings, Figure 1 is a front view of a door and its casings, showing the location of my improved mechanism thereon. Fig. 2 is a horizontal section of the door, jambs, and casing, showing my improved mechanism for latching and opening the door in its constructive details and in its arrangement in relation to the door and casings. Fig. 3 is a side view of the casting or box containing the latch devices. Fig. 4 is a front view of the push-button stud and its escutcheon. Fig. 5 shows the form of the latch-dog, and Fig. 6 shows the form of the rocker or lever for retracting the latch-dog.

Referring to parts, A denotes the door, B the jambs, and C C' the face casings or finish as employed in any building or structure.

D indicates the casting or frame containing the latch-dog F, rocker G, and spring I. Said frame is made of suitable size and shape to contain the parts, and is adapted to fit into a mortise in the side of the door-jamb rabbet, as indicated, its face-plate d being let in flush with the rabbet surface. The latch-dog F is

formed, as shown in Figs. 2 and 5, with an angular latching-nose and a backwardly-extended tail. It is pivoted in the frame at 2, 55 so that its nose swings out through an opening in the face-plate and engages a recess f in the edge of the door. A suitable guard-plate E is best provided on the door for forcing back the dog when the door closes. The 60 rocker G is pivoted in the frame at 3, and its head 4 rests against the tail of the latch-dog. The spring I is confined between the tail of the latch-dog and the side of the frame, each of said parts being fitted with a recess i for 65 the retention of the ends of the spring, as shown. The spring I acts expansively and tends to force the dog forward into engagement with the door-recess. A lug 5 is formed at the tip of the latch-dog, which strikes the 70 inner side of the face-plate and serves to prevent the dog from swinging too far forward. The frame D is provided with a cap-plate D', that is held by screws at e. This cap is removed in the view Fig. 2, so as to show the 75 arrangement of the operating parts.

K indicates a push pin or stud that acts against the rear end of the rocker and extends through the front casing C, and presents a button or thumb-knob at the front of 8c said casing, and K' indicates a push-pin or stud that acts against the head of the rocker and extends through the rear casing C' and presents a button or knob at the exterior of 85 said casing. The push-button stud is surrounded by an escutcheon H, fixed to the door-casing by screws h, and the stud is shouldered or fitted with a lug or equivalent stop that strikes against the inner side of the escutcheon, and thus prevents the push-button from 90 projecting too far at the front of the escutcheon. The inner part of the stud is best made square and enters a corresponding opening in the sides of the latch-frame, as indicated. In cases where the door is approached from 95 one side only, then only a single push-stud K will be used, the rear push-stud K' simply being omitted.

At the hinging edge of the door a spring-actuated presser is fitted in the side of the 100 jamb. This consists of a push-stud M, arranged in a suitable frame m, fitted into a hole or mortise in the jamb B', and having a spring M' about its shank that tends to force

the stud outward against the rear edge of the door. When the door is closed, the stud is pressed down, so that its end is flush with the rabbet surface.

5. A simple handle or knob P is fixed to the door for use in swinging the door or to close it; but this handle is not connected with the fastening mechanism.

The operation is as follows: When pressure is applied to one of the push-button studs K or K', the rocker G is caused to press back or retract the latch-dog, and the instant its point is released from the recess f the presser M acts to throw open the door, as indicated by dotted lines, Fig. 2.

10 My improved mechanism affords a means whereby the opening of the door can be effected by any action that will bring pressure on the push-stud K or K'. Thus it will be seen that a person can readily operate the mechanism, even though the hands are filled 20 with articles.

I claim as my invention herein to be secured by Letters Patent—

25 1. The within-described mechanism for securing and opening doors, consisting of a retractile latch supported in the jamb B and engaging a recess in the edge of the door, a push-button stud projecting through the face-casing, with its inner end engaging for operation and retracting said latch when said button is pressed, and a spring-actuated presser supported in the opposite jamb B' and normally pressing against the hinging edge of 30 the door, all substantially as set forth.

35 2. The combination, with the latch-frame

D, that is adapted to be fitted into the side of the jamb, of the swinging latch-dog F, pivoted at 2, the rocker-piece G, pivoted at 3, the spring I, supported between the latch-dog and 40 frame, and the push-pin K, its inner end resting against said rocker-piece and having at its outer end a button or knob at the front of the casing, for the purposes set forth.

3. The pivoted latch-dog F, having the 45 backwardly-extended tail and the projecting nose for engagement with a recess f in the edge of the door, the rocker G, centrally fulcrumed in the frame, with its head engaging with the tail of the latch-dog, the push-stud 50 K, acting against the tail of the rocker and projecting through the front casing C, the push-stud K', acting against the head of the rocker and projecting through the rear casing C', and the yielding spring I, disposed beneath the tail of the latch-dog, all constructed and combined for operation substantially as 55 and for the purposes described.

4. The combination, with the door, the jamb to which the door is hinged, and retractile-latch mechanism, of the spring-actuated presser, consisting of the rounded stud M, its supporting-frame m, and spring M', adapted for insertion into the jamb-face at the hinging edge of a door, substantially as 60 65 and for the purpose set forth.

Witness my hand this 22d day of April, A. D. 1890.

CHARLES H. WOODCOCK.
